OTIS C. FUNDERBURK, OF BOSTON, MASSACHUSETTS.

VALVE FOR INTERNAL-COMBUSTION ENGINES.

Application filed March 10, 1921. Serial No. 451,082.

My invention relates to valves for internal combustion engines and to the operating mechanism therefor. More particularly it has to do with poppet valves which are operated by a valve tappet and cam on a cam shaft.

Heretofore, as is well understood by those skilled in the art, it has been customary to provide a valve tappet which is separated from the end of the valve stem by a clearance which is adjusted in accordance with the conditions under which the engine operates. This clearance has rendered the engine noisy because the valve tappet, especially when the engine is running at high speed, strikes the lower end of the valve stem a violent blow which can be distinctly heard. The noise can be reduced by reducing the clearance, but heretofore, so far as I am aware, it has not been possible to do away with the clearance altogether, and even the small amount of clearance which is provided where the valves are carefully adjusted, results in noises which can be distinctly heard. In fact, it is commonly said that every engine has one noisy valve by which is meant that one valve always makes more noise than the others, and that its sound catches the ear so that if this valve is readjusted to produce less noise, the ear will then hear the valve which is producing the next greatest amount of noise.

Accordingly, my present invention has for its object to produce a valve operating mechanism which will altogether eliminate the clearance in question and consequently any noise produced by the valve tappet striking the valve. This is accomplished by interposing in the train of mechanism between the valve and the valve member a column of liquid under pressure, the liquid being preferably oil, which being substantially incompressible but variable in quantity, always holds the valve tappet in contact with the underside of the valve. The result is that the noise in question is altogether eliminated and a remarkable improvement in the quiet running of the engine is produced.

The invention will be fully understood from the following description when taken in connection with the accompanying drawings, and the novel features thereof will be pointed out and clearly defined in the claims at the close of this specification.

In the drawings Fig. 1 is a vertical section of a valve operating mechanism embodying my invention.

Fig. 2 is a section on line 2—2 of Figure 1.

Fig. 3 is a view similar to Figure 1 and shows a valve operating mechanism embodying my invention in modified form.

Fig. 4 is a section on line 4—4 of Figure 3.

Referring now to the drawings, at 11 is shown a poppet valve having a valve stem 12 moving in a removable guide 13 positioned in the engine block. On the valve stem 12 is a collar 15 against which rests the valve spring 16, this being the usual valve spring which operates the valve. At 17 is shown a cam on the usual cam shaft. This cam acts on a cam roll 18 mounted on the lower end of a sliding member or piston 19 which, together with another sliding member or piston 20, may be said to form a two-part tappet, the parts being separated by a body or column of liquid which in this case is oil, all as will be hereinafter described. It will be understood of course that I do not limit myself to the use of the roll tappet since any of the well-known types of tappets may be employed.

The upper member 20 is provided with a stem 21 which is always in contact with the lower end of the valve stem 12. The valve tappet members 19 and 20 are both cylindrical in form, and in fact form hollow pistons which travel in a tubular cylinder 22 in the engine casing. The proximate faces of the pistons are hollowed out, as shown at *a* and *b* and separated from each other by the clearance *c*. At *d* is shown a port through the side wall of the cylinder 22 to permit the entrance of oil to the space between the two pistons 19 and 20. The port *d* communicates with an oil passage *e* and pipes 23 and 24. The passage *e* is closed by a valve 25 actuated by a spring 26, the return of oil from the cylinder 22 to the pipe 24 being thus prevented. The stem of this valve 25 is conveniently guided in a screw-threaded cap 27 inserted in the side of the cylinder 22. The pipe 24 communicates with the pressure feed oiling system (not shown) of the engine so that oil under pressure flows through the pipe 23, passage *e*, past the valve 25, and through the port *d* into the space *c* between the proximate faces of the pistons 19 and 20. Being

under pressure, the oil pushes the piston 20 upward until the end of the spindle 21 strikes the valve stem 12 which stops it, since the valve spring 16 is strong enough to 5 resist movement of the piston 20 due to the oil. The result is that the piston 20 and valve stem 12 and the cam follower 18 and cam 17 are always maintained in contact with each other. Oil which leaks by the 10 pistons 19 and 20 and escapes, is replaced by oil flowing past the valve 25. When the engine is running, the motion produced by the cam 17 is communicated to the valve 12 through the interposition of the column 15 of oil contained in the space between the proximate faces of the pistons 19 and 20. Since liquids are substantially incompressible, the several parts have the effect of a unitary rigid valve stem without any clearance, and all noise from these parts is completely eliminated. Any expansion due to heat is cared for by the leakage, and contraction is overcome by the pressure in the oiling system of the engine which keeps the 25 space between the proximate faces of the pistons constantly full of oil.

In Figures 3 and 4, I have shown a slightly modified form of my invention. In these figures, the valve is designated 30, the valve 30 spring 31 and the piston members 32 and 33. The space between the piston members is designated *g*. A spring *s* is inserted between the piston members to hold them apart. The oil is supplied to the space *g* 35 from the passage *h* in the hollow cam shaft 34 in the following way:—At 35 is shown one of the bearings for the cam shaft. This bearing is cut away on the interior to form a groove *j* which extends about the interior 40 of the bearing for about 150 degrees. At *k* is shown a port leading from the interior of the cam shaft, the end of the port being located in position to register with the passage *j* during a considerable part of the 45 revolution of the cam shaft. A pipe 36 leads from the passage *j* to the space *g* between the proximate faces of the pistons communicating with said space by a series of small ports *l*.

From the foregoing, it will be seen that 50 the passage from the oiling system through the hollow bore *h* of the cam shaft, port *k*, passage *j* in the bearing ring and pipe 36 is open to the space between the pistons during 55 150 degrees of the revolution of the cam shaft and is closed during the remainder of the revolution, being closed at the time when the poppet valve 30 is opened by the cam.

It will therefore also be seen that the construction described operates as a positively 60 actuated valve to retain the oil in the oil column while the cam is opening the valve. Any expansion of the valve stem is cared for by displacement of oil which is forced back through the passage 36 when the groove registers with the port in the cam shaft through which the oil is fed.

It will be seen in connection with both embodiments of my invention that the device will operate even if there is no oil in the 70 chamber between the pistons, because in that case the pistons will be in contact with each other and will act as a unitary valve tappet, the only difference being that the valve lift will be somewhat diminished. This is an 75 important feature of my invention because the engine will start satisfactorily before there is oil pressure enough in the lubricating system to fill the chambers, and will continue to operate satisfactorily even after the 80 pressure in the lubricating system drops below the pressure necessary to fill the chambers in the valve operating mechanism.

What I claim is—

1. The combination with a poppet valve, 85 of operating mechanism therefor which includes a column of oil, and means connecting with the oiling system of the engine for replenishing said column of oil, said replenishing means comprising a cam shaft provided with a longitudinal opening through which oil is supplied under pressure, a radial passage leading from said longitudinal opening, and means for placing said radial passage in communication with said column 90 of oil during a part of each revolution of said shaft.

2. In combination with a poppet valve, a valve spring therefor and a cam shaft having a cam thereon, a valve tappet in two 100 parts, a column of oil separating said two parts and means for replenishing the column of oil which includes a longitudinal opening in said cam shaft through which oil is supplied under pressure, a radial passage 105 leading from said longitudinal opening, an annular bearing on said shaft having a groove of limited extent on its interior surface, said radial passage being in communication with said groove during a part of each 110 revolution of said shaft and closed when said valve is opened by said cam, and means for placing said groove in communication with said column of oil.

In testimony whereof I affix my signature.
OTIS C. FUNDERBURK.
